UNITED STATES PATENT OFFICE.

WILLIAM B. FLANAGAN, OF BROOKLYN, NEW YORK.

DESIGN FOR A VEGETABLE RECEPTACLE.

Application filed May 5, 1928. Serial No. 26,589. Term of patent 3½ years.

To all whom it may concern:

Be it known that I, WILLIAM B. FLANAGAN, a citizen of the United States, residing at Brooklyn, in the county of Kings and State of New York, have invented a new, original, and ornamental design for Vegetable Receptacles, of which the following is a specification, reference being had to the accompanying drawing, forming part thereof.

The figure is a perspective view of a vegetable receptacle showing my new design.

The perforations shown in the various panels are continued throughout the areas of said panels.

I claim:—

The ornamental design for a vegetable receptacle, as shown and described.

WILLIAM B. FLANAGAN.
